W. S. MAYO.

Water Back for Ranges, &c.

No. 28,096.

Patented May 1, 1860.

Inventor:
W. S. Mayo.

UNITED STATES PATENT OFFICE.

WILLIAM S. MAYO, OF NEW YORK, N. Y.

WATER-BACK FOR RANGES, &c.

Specification of Letters Patent No. 28,096, dated May 1, 1860.

To all whom it may concern:

Be it known that I, Wm. S. Mayo, of the city of New York, State of New York, have invented a new and Improved Water-Back 5 Capable of Resisting the Bursting Power of Freezing Water.

It is well known that no water-back, of the kinds now in use, will stand without cracking when the water in the water-back 10 is suffered, from any cause, to freeze and it is equally well known that such accidents are frequently happening, especially in the city of New York, every winter, and that they occasion a great deal of trouble and ex- 15 pense.

The nature of my invention consists in making a water-back, of any shape or form, into which is inserted a compressible and elastic body or substance which will allow, 20 by its compression, room for the expanding ice, and thus take off the pressure from the sides of the water-back.

At present, I prefer making the compressible body of cork covered with lead, 25 but it may be made of other elastic substances or of metal springs covered with flexible metal covers, or of thin tubes or cases strong enough to stand the pressure of the

water and the steam, but capable of being crushed by the greater pressure of the ice, 30 with the disadvantage however in this last case of being useful only one time. Cork covered with lead has been proved by repeated experiment to be perfectly effectual and it is what I now prefer.

In the drawing A represents a water-back with the front taken out so as to show B the rows of cork or corks covered with lead fixed by a rod of iron to the back part of the water-back.

C represents an opening closed with a screw cap through which the compressible body or bodies are introduced into the water-back.

What I claim as my invention and desire 45 to secure by Letters Patent is—

A water-back with a compressible body or substance of whatever form or material which being placed inside the water-back shall take off the pressure of freezing water 50 and prevent the water-back from bursting when exposed to frost.

W. S. MAYO.
